(21) Appl. No.: **29/172,176**

CLAIM

(22) Filed: **Dec. 5, 2002**

The ornamental design for an exiting spiral spline female pipe coupling, as shown and described.

(51) **LOC (7) Cl. 23-01**

DESCRIPTION

(52) **U.S. Cl. D23/262**

FIG. 1 is a back elevational view of an existing spiral spline female pipe coupling showing my new design;

(58) **Field of Search D23/262, 266, D23/259; 285/333, 390**

FIG. 2 is a top projection view thereof showing the spiral internal spline seat ending at the external exit port, and a portion of the recessed gasket seat;

(56) **References Cited**

FIG. 3 is a left side elevational view thereof;

U.S. PATENT DOCUMENTS

FIG. 4 is a top elevational view thereof;
